HOLDER FOR CARDS AND PHOTOGRAPHS

Marchand B. Hall, Chicago, Ill., assignor to Acme
Visible Records, Inc., Chicago, Ill., a corpora-
tion of Delaware

Application April 13, 1945, Serial No. 588,156

6 Claims. (Cl. 129—16.7)

1

This invention relates to improvements in holders for mounting and supporting cards, photographs and the like, and more particularly to the provision of a holder having novel retaining means formed thereon.

It is an object of the present invention to adapt a generally conventional holder of standard size and of the class comprising a holder body having a sheath embracing the lower marginal edge thereof and a plurality of slits or slots formed adjacent the upper marginal edge thereof, for the reception of pairs of cards or photographs of standard size in a compact arrangement which has heretofore been difficult to attain.

Other objects relate to the details of construction, arrangement of parts and the economies thereof which will be apparent from a consideration of the following specification and drawings, wherein:

Fig. 1 is a front elevational view showing a holder embodying my invention, and

Fig. 2 is a rear elevational view thereof.

Fig. 3 is a section on the line 3—3 of Fig. 1.

Fig. 4 is a fragmentary view of the holder body of Fig. 1 illustrating the novel holder means characterizing the present invention.

Fig. 5 is a view similar to that of Fig. 4, of modified construction.

Referring to the drawings, the reference numeral 10 indicates a holder body of flexible sheet material having a hinge 11 defined by the line of perforations 12 and thereby adapted for flexible mounting in a suitable holder or binder by means of a suitable hanger, not shown. Although not illustrated, other conventional hinge mounting means for the holder may be employed. In like conventional manner the holder body 10 has a sheath 13 embracing the lower marginal edge thereof, which sheath may be of a transparent plastic such as Celluloid, secured thereto by the staples 14 adjacent the side edges of the body. An intermediate staple 15 may be employed engaging at least one face of the sheath to the holder body. The sheath 13 is adapted for reception of the lower marginal edges of cards or photographs to be mounted on the holder, and for reception of certain of the upper corners of such mounted articles, the holder body 10 adjacent its side edges is provided with the obliquely extending slot pairs 16 and 17 adjacent its upper marginal edge. Thus by means of the sheath 13 and the slot pairs 16 or 17, cards or photographs can be mounted on both faces of the holder, as conventional.

2

A holder of such class, and as illustrated in Figs. 1 and 2, in for example a standard size of 8 x 10, while suitable for mounting 8 x 10 inch photographs on one or both faces, has been heretofore considered too narrow in width to be adapted for the support of two 5 x 7 inch photographs on one or both faces. However, in accordance with the present invention such standard size holder has been adapted for the reception of pairs of 5 x 7 photographs on one or both faces, or a pair on one face and an 8 x 10 photograph or card on the opposed face, in a manner whereby the 5 x 7 inch cards or photographs are engaged by supplementary holder means 15 which prevents their lateral displacement while retaining them in close proximity.

Thus, in accordance with the present invention, I provide an inwardly disposed tongue 18 medially of the holder body, and defined therefrom by the slit 19 which slit may be of arcuate form such as an arc of 180° in extent, the opposed ends of the slit having their inception on a line parallel to a holder edge, such as the illustrated upper marginal edge of the holder and adjacent thereto. A pair of offset slits 20 and 21 are further provided, both parallel to slit 19, each extending in opposite directions from a line bisecting tongue 18 to its respective ends, these slits 20 and 21 being suitably of 90° arcuate extent when slit 19 is of 180°. The slit 20 is formed on the tongue 18 whereas the slit 21 is formed on the holder body, both being substantially equally spaced from slit 19.

As shown in Fig. 1, a pair of inserts 22 and 23, such as cards or photographs may be mounted on the holder by inserting their lower edges within the sheath 13 and the outer upper corners within the diagonal slots 16. The upper inner corner of the card 22 is inserted through the slits 21 and 19 and held by the strip 26 formed between them, and the inner upper corner of the card 23 is inserted through the slits 19 and 20 and held by the strip 27 formed on the tongue, permitting the two cards to be mounted in very close and substantially touching relationship and yet held against lateral displacement, the adjacent and contiguous ends of the strips 26 and 27 providing firm abutments.

As shown in Fig. 2, a pair of cards or photographs 24 and 25 may be mounted on the opposed face of the holder body 10 in like fixed position. Thus the lower edges of the cards are extended within the sheath 13 and their outer upper corners within slots 16. The inner upper corner of card 24 is inserted through slit 20 and

the inner upper corner of card 25 through slit 18.

When a center staple 15 is employed in engagement with only one leg of the sheath 13, a pair of 5 x 7 photographs may be mounted on one face of the holder and an 8 x 10 photograph on the opposed face with its upper corners extended through diagonal slots 17.

When a card holder or album is provided with a number of holders, some of which are as yet unused, and for the purpose of preventing the tongues 18 from becoming bent before use, it may be found desirable to cause the tongue 18 to be temporarily held down. This I accomplish by interrupting the slit 19, preferably medially, by a rupturable body component 28 as shown in the modified form of Fig. 5, mere insertion of the 5 x 7 cards or photographs being sufficient to cause severance permitting a pair of adjacent cards to be brought and held in substantially touching edgewise relationship to each other.

Although I have illustrated and described the preferred forms of my invention, it will be obvious to those skilled in the art that various modifications may be made without departing from the spirit thereof, and I therefore do not wish to be limited thereto except as set forth in the following claims.

I claim as my invention:

1. A holder for inserts such as cards, photographs and the like comprising a body and a plurality of insert engaging means provided thereon, one of said insert engaging means being constructed and arranged to receive in close proximity the adjacent corners of pairs of inserts mounted on the opposed faces of said holder and comprising an inwardly disposed tongue formed on said body and a pair of offset slits formed parallel to the free end of said tongue, one being formed on said tongue and the other on the holder body and extending in opposed directions from a line bisecting said tongue.

2. A holder for inserts such as cards, photographs and the like comprising a body and a plurality of insert engaging means provided thereon, one of said insert engaging means being constructed and arranged to receive in close proximity the adjacent corners of pairs of inserts mounted on the opposed faces of said holder and comprising an inwardly disposed tongue defined by a substantially continuous slit formed on said body, the opposed ends of said slit at the root of the tongue terminating on a line parallel to one edge of the holder, and a pair of oppositely extending offset slits each extending from said line to a line bisecting said tongue and parallel to said first slit, one of said offset slits being formed on said tongue and the other on said holder body.

3. A holder for inserts such as cards, photographs and the like of the class described comprising a body and a plurality of insert engaging means provided thereon including a pair of strips defined by slits formed in said body for receiving in close proximity the adjacent corners of a pair of inserts mounted upon one side of said holder, each of said strips extending from a line parallel

to one edge of said holder and inwardly therefrom to a line normal thereto and separately terminating thereon in spaced substantially contiguous relationship to each other.

5. A holder for inserts such as cards, photographs and the like comprising a body and a plurality of insert engaging means provided thereon, one of said insert engaging means being constructed and arranged to receive in close proximity the adjacent corners of pairs of inserts mounted on the opposed faces of said holder and comprising an inwardly disposed tongue defined by an arcuate slit formed in said body, and a pair of offset slits parallel thereto, one being formed on said tongue and the other on said body and extending in opposed directions from a line bisecting said first slit.

20 6. A holder for inserts such as cards, photographs and the like comprising a body and a plurality of insert engaging means provided thereon, one of said insert engaging means being constructed and arranged to receive in close proximity the adjacent corners of pairs of inserts mounted on the opposed faces of said holder and comprising an inwardly disposed tongue defined by an arcuate slit formed in said body, and a pair of offset slits parallel thereto, one being formed on said tongue and the other on said body and extending in opposed directions from a line bisecting said first slit, said first slit being substantially medially interrupted by a rupturable body component.

25 7. A holder for inserts such as cards, photographs and the like comprising a body and a plurality of insert engaging means provided thereon, one of said insert engaging means being constructed and arranged to receive in close proximity the adjacent corners of pairs of inserts mounted on the opposed faces of said holder and comprising an inwardly disposed tongue defined by an arcuate slit of 180° extent formed in said body, and a pair of offset slits parallel thereto to each of 90° extent, one of said 90° slits being formed on said tongue and the other on said body and extending in opposed directions from a line bisecting said 180° slit.
